(57) **CLAIM**

The ornamental design for the handle, as shown and described.

DESCRIPTION

FIG. 1 is a perspective view of a handle showing our new design;

FIG. 2 is a top plan view thereof;

FIG. 3 is a bottom plan view thereof;

FIG. 4 is an elevational view of one side thereof; the other side elevational view being identical; and,

FIG. 5 is a rear elevational view thereof.

The broken lines are for illustrative purposes only and forms no part of the claimed design.
